(57) **CLAIM**

The ornamental design for a display package, as shown and described.

DESCRIPTION

FIG. 1 is a perspective view of a display package, showing our new ornamental design;

FIG. 2 is a front view thereof;

FIG. 3 is a back view thereof;

FIG. 4 is a left-side view thereof;

FIG. 5 is a right-side view thereof;

FIG. 6 is a top view thereof; and,

FIG. 7 is a bottom view thereof.

The dashed/dotted and broken lines depict environmental subject matter only and form no part of the claimed design.
